TYPEWRITER ERASER HOLDER

Louis C. Neff, Brooklyn, N. Y.

Application October 26, 1934, Serial No. 750,117

12 Claims. (Cl. 120—36)

The invention relates to typewriter eraser holders, and more particularly to a holder permitting erasures to be made by a typist without grasping the eraser in the fingers.

5 The ordinary circular typewriter eraser consists of a disc of soft vulcanized rubber having an abrasive in the filler used, this disc being held between two metal plates connected by a tubular rivet.

10 When using such an eraser, the typist grasps the eraser and rubs the portion of the paper from which the erasure is to be made, fairly hard pressure being developed. Most erasures are made while the inked impression is fresh, so that 15 there is a tendency to smut the paper, even though a typist may exercise great care to keep the eraser clean, with movement of the eraser, and also to smut the edge of the eraser. This condition is greatly accentuated when the erasure is to be made from carbon copies of an original 20 document. Smut upon the paper requires additional rubbing to remove same, and smut upon the edge of the eraser not only interferes with the making of a clean erasure, but actually increases the amount of smut to be removed from 25 the paper upon which an erasure is being made. To avoid this condition, the typist not only has to change the position of the eraser to bring fresh portions into contact with the paper, but at 30 times is compelled to clean the accumulated smut from the eraser before attempting to make an erasure.

The effectiveness with which an eraser can be used, particularly when erasures are to be made 35 upon sheets while in a typewriting machine, is dependent upon the circular form and a proper width of the periphery of the eraser, since with an eraser having a flat or flattened surface the action cannot be applied or limited, even with the 40 use of an ordinary pierced shield, to the spot upon the paper from which the erasure is to be made.

When grasping a circular eraser in the fingers, the tendency is to develop excessive pressure 45 against the paper, and the smutting of the paper and of the eraser, at times, causes a prolonged rubbing action, sufficient to wear a hole completely through the paper, necessitating the re-writing of a document. Furthermore, when so 50 grasping the eraser, the fingers and hand become smutted from the eraser and from contact with carbon paper, or portions of the paper from which erasures are not being made.

With the ordinary circular eraser, there is a 55 tendency on the part of a typist to use the sides

at the periphery of the eraser in an effort to bring a clean surface into contact with the paper, and to allow the typist to clearly observe the work being done. This tilting of the eraser tends to narrow its edge so as to seriously interfere with the contact of a sufficient width of the eraser with a desired width of paper. The narrowing or thinning of the edge of the eraser also tends to cause it to so flex as to interfere with a proper abrasive action.

Even with the most highly skilled typist, the necessity for making erasures is of frequent occurrence because of mechanical conditions in a typewriter. When operating at the higher typewriter speeds, there is a tendency to transpose 15 letters and to pile impressions of succeeding letters.

It is obvious that the time required to make erasures, to clean an eraser, and to keep the hands of the typist clean, impairs the efficiency 20 of the typist.

With the above conditions in mind, I have provided a typewriter eraser holder so constructed that an ordinary circular eraser may be revolvably mounted in a position to permit it to be 25 used without the necessity for the typist touching any part of the eraser, the holder including a member engaging the periphery of the eraser with a variable, controlled pressure sufficient to prevent a free turning thereof while allowing it 30 to turn with short, restrained impulses during a part of each reciprocation when making an erasure, so as to clean smut from, and recondition, its periphery in a manner to ensure at all 35 times an effective, clean edge surface.

A holder embodying the invention is grasped in the palm of the hand, so that the thumb or other part of the hand is so positioned as to afford an unobstructed view of the portion of the paper upon which the eraser is acting. The positioning of the hand out of the line of vision prevents contact thereof with the typewritten sheet, or with carbon paper folded away from the sheet from which matter is being erased. Hence, soiling or smutting of the hand is prevented.

The grip of the holder extends radially of the eraser, and the position of the hand and the development of pressure by the forefinger closely adjacent the eraser, but not in contact therewith, permits the eraser to automatically follow the 50 rounded surface of a typewriter platen, and avoids likelihood of excessive abrasive action, due to the curvature of the platen, upon any portion of the letter or letters to be erased as the eraser 55

is given a series of short rapid reciprocations in an apparent straight line.

While the constant re-conditioning and cleaning of the periphery of the eraser ensures a desired contact area between the eraser and the paper, the form of the holder and manner of using same is such as to permit lateral tilting of the eraser, if such be desired, to ensure a uniform, clean erasure of the matter to be removed.

10 The construction of the holder is such as to necessitate the use, in its production, of few parts and a simple assembling operation, and these parts are so constructed and arranged as to be readily understandable even by those not mechanically inclined.

15 The form and arrangement of the parts is also such as to permit the quick and convenient removal of an excessively worn eraser and the substitution of a new one therefor.

20 The holder includes no parts which by breakage would make the holder inoperative, and if the parts should become separated, they can readily be reassembled without the aid of tools.

25 The invention consists primarily in a typewriter eraser holder embodying therein an elongated hand grip having one end thereof formed to provide a bearing seat adapted to engage the palm of the hand, means whereby a circular eraser may be detachably and rotatably mounted adjacent the other end of said grip, and a manually operative presser arm mounted for unrestrained movement towards and from said means toward said bearing seat end of said grip and extending at an angle into engageable relation 30 with the periphery of an eraser adjacent the top thereof, whereby a variable, manually controlled erasing pressure upon an eraser may be developed with resultant resistance to its turning and in such other novel structural characteristics as are hereinafter set forth and described, and more particularly pointed out in the claims hereto appended.

40 Referring to the drawing,

Fig. 1 is a perspective view of a typewriter eraser holder embodying the invention, a circular eraser being indicated in dotted lines;

45 Fig. 2 is a bottom plan view of the presser arm detached from the hand grip; and

50 Fig. 3 is a view upon an enlarged scale of a modified form of presser arm.

55 Like numerals refer to like parts throughout the several views.

In the embodiment of the invention shown in the drawing, the hand grip 10 is formed of sheet metal, affording side bars 11 and 12 connected by a loop 13 at one end thereof. This handle is of a length to be firmly grasped in the hand of the user with the looped end 13 thereof bearing upon the palm of the hand.

60 Adjacent the free end of each side bar 11-12 is an inwardly directed bearing stud 14-15 adapted to enter the tubular rivet connecting the side plates of an ordinary circular eraser in a manner to permit the free rotation of said eraser between said side bars. Said bearing studs 14 and 15 may be short stud rivets, or the material of the side bars may be drawn into the desired form of a bearing for the tubular rivet of the eraser.

65 70 Half hard, cold rolled steel, brass or other metal may be used in the production of the hand grip, and in forming said hand grip the side bars 11 and 12 may be forced together to an extent to develop sufficient resiliency toward the free ends thereof to prevent the accidental

75 escape of an eraser, due to the spreading of said arm. This will not interfere with the free rotation of the eraser.

80 As will more fully appear hereinafter, the construction of the holder is such that during repeated reciprocations of the eraser, when making an erasure, it will be held firmly against rotary movement in one direction, and will turn slowly in its bearings 14 and 15 during reciprocation in the opposite direction, sufficient resistance being offered to this turning movement to so limit the amount thereof as to ensure some abrasive action during this movement. The amount of pressure exerted upon the paper from which the erasure is being made, and the degree of the 85 turning movement of the eraser, in the manner above described, is manually determined and controlled by the typist through the medium of a presser arm 16 mounted toward the looped end of the hand grip and extending upwardly from 90 said grip at an angle into engageable relation with the periphery of an eraser adjacent the top thereof.

95 This presser arm 16 is preferably made of hardened flexible steel and the end thereof, engageable with the periphery of an eraser, is roughened, as shown at 17, to afford an abrasive surface which, during the turning movement of the eraser, will gradually wear down the periphery thereof so as to remove any dirt or smut 100 thereon, thus affording at all times a clean contact surface.

105 Circular erasers, when new, have a rounded periphery and, to preserve this contour of the edge of the eraser, I transversely arch the end 110 of the presser arm, adjacent the roughened portion thereof, so that while the edge of the eraser is being cleaned, it will also be reconditioned or restored to its original curved form.

110 To facilitate the mounting of the presser arm 16 upon the hand grip, I preferably provide said arm, at the end thereof opposite to that which engages an eraser, with lateral trunnion forming ears 18 adapted to enter openings 19 in the side bars 11 and 12 respectively. This construction permits a free pivotal movement of the arm to permit the roughened end thereof to accommodate itself to the changing diameter of the eraser with prolonged use, without requiring any material variation in the pressure developed 115 through this arm upon the periphery of the eraser with such changing diameter thereof.

120 If a rigid connection be provided between the ears or trunnions 18 and the side bars 11 and 12, excessive flexure of the arm 16 is required to 125 maintain it in contact with the eraser with the lessening of its diameter.

130 In the production of the arm 16, a blanking die is used and the transverse curvature at one end of the arm, and the teeth constituting the 135 roughened portion 17, may be formed by means of the same die. In time, the teeth of the portion 17 will become worn from the action thereon of the abrasive in the eraser. The use of hardened steel ensures a satisfactory life of this part of the 140 holder, but other materials and manufacturing methods may be employed which will prolong the life of the arm, but such materials and such methods tend to increase the cost of production to an extent to be impracticable for an inexpensive article of this character.

145 In Fig. 3 of the drawing, I have shown a construction of presser arm which, when used, will double the life of the holder. In this embodiment of the invention the presser arm proper is shown 150

at 16a and the ears or trunnions at 18a. Instead of arching the free end of the arm, as herein-after described, this arm is made of thicker stock than the arm 16 and the end thereof, is swaged 5 to concavely arch both sides of the arm, simultaneously with the formation of the teeth or roughened surfaces thereon. In this form of the invention one of the arched roughened surfaces is shown at 17a and the reverse arched roughened 10 surface at 17b.

With this form of presser arm, a pivotal connection between the arm and the hand grip is essential since the arm may project from either side of the hand grip, according to whether the 15 portion 17a or the portion 17b is to be engaged with the periphery of the eraser.

I prefer to employ the form of arm shown in Figs. 1 and 2, because with the thinner stock of 20 which the arm is made, the material of said arm has inherently greater flexibility and permits a more convenient use of the holder.

The manner of use of a holder embodying the invention is substantially as follows:—

To mount a circular eraser in the holder, it is 25 merely necessary for the user to spread the bars 11 and 12 and pass the eraser between the bars, which, when released, will close upon the eraser with the bearing studs 14 and 15 within the ends of the hollow rivet or other opening through the 30 eraser.

When it is desired to erase one or more letters, the typist grasps the hand grip 10 with the loop portion thereof engaging the palm of the hand, and the forefinger engaging the presser arm 16 35 adjacent the area of contact of said arm with the eraser. When grasped in this manner, the edge of the eraser contacting with the sheet of paper is positioned well forwardly of the hand, so that the typist can observe the action of the eraser. This position of the hand affords a clear line of 40 vision to the work, whether the eraser be held in a true vertical position or tilted slightly to one side or the other.

The desired contact pressure between the 45 eraser and the paper is developed by the action of the forefinger upon the member 16. The extent of this pressure may be varied at will and the action will be practically automatic. As the eraser is being rubbed back and forth upon the sheet, movement away from the typist will be accompanied by a slight turning movement of the 50 eraser by reason of the lowered resistance to turning of the eraser because of the forward and upward angle of the arm 16. With the movement 55 of the eraser toward the typist, however, the resistance to turning movement will be sufficiently great to hold the eraser stationary so as to get the maximum abrasive action upon the paper. Sufficient pressure may be applied to the arm to 60 prevent turning movement of the eraser in either direction, and this pressure of the forefinger may be relieved only when it is desired to permit the turning of the eraser. When this pressure is so relieved, the eraser will turn during its movement 65 away from the typist.

This mode of operation results because with movement of the eraser forwardly or away from the typist, the resistance to the turning movement is relatively lower than with movement in the opposite direction, due to the wedging action 70 developed during the latter movement from the angularity of the arm 16 and the yieldability of the material of the eraser.

With the turning of the eraser, the portion 75 thereof engaged with the roughened portion 17

of the arm 16 will abrade the surface of the eraser sufficiently to remove any smut thereon, and will, at the same time, remove any flattened surfaces of the eraser due to the rubbing action. Consequently, the eraser will always have a true, 5 circular, clean, transversely arched periphery.

With the use of a holder embodying the invention, no ragged edges on the eraser are developed, nor will the edge of the eraser become worn at the sides to develop a highly flexible edge 10 about the eraser.

With the use of a holder embodying the invention, the diameter of the eraser is gradually reduced and the flexibility of the arm 16, or this flexibility coupled with the pivotal support of the 15 arm, causes the roughened surface thereof to have movement radially of the eraser so as to constantly engage same.

The constant cleaning and re-forming of the 20 surface of the eraser avoids all smutting of the paper by the ink or carbon reproduction. The pressure required to make an erasure is considerably less than that which is used when grasping the eraser in the fingers. Consequently, the likelihood of wearing a hole in the paper is reduced to a minimum.

The length of the hand grip not only avoids 25 contact of the hand with a smutted eraser, but keeps the hand away from the surface from which the erasure is being made and carbon sheets 30 folded away from the typewriter platen. No smut will be transferred from the eraser to the sheet from which the erasure is being made.

Most erasures are made while the printed sheet is upon the rounded surface of the typewriter 35 platen. The application of pressure by the forefinger causes the eraser to follow the curvature of the platen, the portion of the hand grip contacting with the palm of the hand acting more or less as a fulcrum point about which the holder 40 turns when following a rounded surface.

With the use of a holder embodying the invention, the eraser is always ready for use without the necessity for cleaning the surface thereof. The eraser always has a properly formed, clean 45 edge, and the typist is relieved from the annoyance and loss of time incidental to cleaning an eraser and cleaning the hands after making numerous erasures.

The time required to make an erasure is less 50 than when gripping the eraser in the hand, the surface of the paper, after the erasure, is smooth and clean, and the amount of effort required is materially less than when gripping the eraser in the fingers.

It is not my intention to limit the invention to 55 the precise details of construction shown in the drawing, it being apparent that such may be varied without departing from the spirit and scope of the invention.

Having described the invention, what I claim as 60 new and desire to have protected by Letters Patent, is:—

1. A typewriter eraser holder embodying 65 therein an elongated hand grip having one end thereof formed to provide a bearing seat adapted to engage the palm of the hand, means whereby a circular eraser may be detachably and rotatably mounted adjacent the other end of said grip, and a manually operative presser arm mounted for 70 unrestrained movement towards and from said means toward said bearing seat end of said grip and extending at an angle into engageable relation with the periphery of an eraser adjacent the top thereof, whereby a variable, manually con- 75

trolled erasing pressure upon an eraser may be developed with resultant resistance to its turning.

2. A typewriter eraser holder embodying there-in an elongated hand grip formed of sheet metal, looped at one end to provide side arms and a bearing seat adapted to engage the palm of the hand, each of said arms having, adjacent its other end, a bearing stud, whereby a circular eraser may be detachably and rotatably mounted in said grip, and a manually operative, flexible metal, presser arm mounted for unrestrained movement towards and from said bearing stud toward said looped end of said grip and extending at an angle into engageable relation with the periphery of an eraser adjacent the top thereof, whereby a variable, manually controlled erasing pressure upon an eraser may be developed with resultant re-sistance to its turning.

3. A typewriter eraser holder embodying there-in an elongated hand grip having one end thereof formed to provide a bearing seat adapted to engage the palm of the hand, means whereby a circular eraser may be detachably and rotatably mounted adjacent the other end of said grip, and a manually operative presser arm pivotally mounted for unrestrained movement towards and from said means toward said bearing seat end of said grip and extending at an angle into engageable relation with the periphery of an eraser adjacent the top thereof, whereby a variable, manually controlled erasing pressure upon an eraser may be developed with resultant resistance to its turning.

4. A typewriter eraser holder embodying there-in an elongated hand grip having one end thereof formed to provide a bearing seat adapted to engage the palm of the hand, means whereby a circular eraser may be detachably and rotatably mounted adjacent the other end of said grip, and a manually operative presser arm mounted for unrestrained movement towards and from said means toward said bearing seat end of said grip and extending at an angle toward, and having a roughened surface adapted to be brought into engageable relation with, the periphery of an eraser adjacent the top thereof, whereby a variable, manually controlled erasing pressure upon an eraser may be developed with resultant resistance to its turning.

5. A typewriter eraser holder embodying there-in an elongated hand grip formed of sheet metal, looped at one end to provide side arms, and a bearing seat adapted to engage the palm of the hand, each of said arms having, adjacent its other end, a bearing stud, whereby a circular eraser may be detachably and rotatably mounted in said grip, and a manually operative, flexible metal, presser arm mounted for unrestrained movement towards and from said bearing stud toward said looped end of said grip and extending at an angle toward, and having a roughened surface adapted to be brought into engageable relation with, the periphery of an eraser adjacent the top thereof, whereby a variable, manually controlled erasing pressure upon an eraser may be developed with resultant resistance to its turning and with turning of the eraser the periphery thereof will be cleaned and re-formed.

6. A typewriter eraser holder embodying there-in an elongated hand grip having one end thereof formed to provide a bearing seat adapted to engage the palm of the hand, means whereby a circular eraser may be detachably and rotatably mounted adjacent the other end of said grip, and a manually operative presser arm pivotally

mounted for unrestrained movement towards and from said means toward said bearing seat end of said grip and extending at an angle toward, and having a roughened surface adapted to be brought into engageable relation with, the periphery of an eraser adjacent the top thereof, whereby a variable, manually controlled erasing pressure upon an eraser may be developed with resultant resistance to its turning, and with turning of the eraser the periphery thereof will be cleaned and 10 re-formed.

7. A typewriter eraser holder embodying there-in an elongated hand grip having one end thereof formed to provide a bearing seat adapted to engage the palm of the hand, means whereby a circular eraser may be detachably and rotatably mounted adjacent the other end of said grip, and a manually operative presser arm mounted for unrestrained movement towards and from said means toward said bearing seat end of said grip and extending at an angle toward, and having a transversely arched roughened surface adapted to be brought into engageable relation with, the periphery of an eraser adjacent the top thereof, whereby a variable, manually controlled erasing pressure upon an eraser may be developed with resultant resistance to its turning, and with turning of the eraser the periphery thereof will be cleaned and re-formed.

8. A typewriter eraser holder embodying there-in an elongated hand grip formed of sheet metal, looped at one end to provide side arms, and a bearing seat adapted to engage the palm of the hand, each of said arms having, adjacent its other end, a bearing stud, whereby a circular eraser may be detachably and rotatably mounted for unrestrained movement towards and from said bearing stud in said grip, and a manually operative, flexible metal, presser arm pivotally mounted toward said bearing seat end of said grip and extending at an angle toward, and having a roughened surface adapted to be brought into engageable relation with, the periphery of an eraser adjacent the top thereof, whereby a variable, manually controlled erasing pressure upon an eraser may be developed with resultant resistance to its turning, and with turning of the eraser the periphery thereof will be cleaned and 40 re-formed.

9. A typewriter eraser holder embodying there-in an elongated hand grip formed of sheet metal, looped at one end to provide side arms, and a bearing seat adapted to engage the palm of the hand, each of said arms having, adjacent its other end, a bearing stud, whereby a circular eraser may be detachably and rotatably mounted for unrestrained movement towards and from said bearing stud in said grip, and a manually operative, flexible metal, presser arm mounted toward said bearing seat end of said grip and extending at an angle toward, and having a transversely arched roughened surface adapted to be brought into engageable relation with, the periphery of an eraser adjacent the top thereof, whereby a variable, manually controlled erasing pressure upon an eraser may be developed with resultant resistance to its turning, and with turning of the eraser the periphery thereof will be cleaned and 50 re-formed.

10. A typewriter eraser holder embodying there-in an elongated hand grip formed of sheet metal, looped at one end to provide side arms, and a bearing seat adapted to engage the palm of the hand, each of said arms having, adjacent its other end, a bearing stud, whereby a circular 70

eraser may be detachably and rotatably mounted in said grip, and a manually operative, flexible metal, presser arm pivotally mounted for unrestrained movement towards and from said bearing stud toward said bearing seat end of said grip and extending at an angle toward, and having a transversely arched roughened surface adapted to be brought into engageable relation with, the periphery of an eraser adjacent the top thereof, whereby a variable, manually controlled erasing pressure upon an eraser may be developed with resultant resistance to its turning, and with turning of the eraser the periphery thereof will be cleaned and re-formed.

11. A typewriter eraser holder embodying therein an elongated hand grip formed of sheet metal, looped at one end to provide parallel spaced side arms, and a bearing seat adapted to engage the palm of the hand, each of said arms having, adjacent its other end, a bearing stud, whereby a circular eraser may be detachably and rotatably mounted in said grip, and a manually operative, flexible metal, presser arm, of a width to pass between the side arms of said grip, pivotally mounted for unrestrained movement towards and

from said bearing stud between said arms and toward said bearing seat end of said grip, and extending at an angle toward, and having upon the opposite sides thereof transversely arched roughened surfaces adapted to be selectively brought into engageable relation with, the periphery of an eraser adjacent the top thereof, whereby a variable, manually controlled erasing pressure upon an eraser may be developed with resultant resistance to its turning, and with turning of the eraser the periphery thereof will be cleaned and re-formed. 5

12. In a typewriter eraser holder an elongated hand grip having one end thereof formed to provide a bearing seat adapted to engage the palm of the hand, means adjacent the other end thereof whereby a circular eraser may be detachably and rotatably mounted upon said hand grip, and a member mounted for unrestrained movement towards and from said means, said means extending from adjacent said bearing seat into engagement with said eraser, whereby pressure may be applied to said member by the forefinger to control the rotary movement of said eraser. 15 20

LOUIS C. NEFF. 25
